(57) **CLAIM**

The ornamental design for a mounting device, as shown and described.

DESCRIPTION

1. Mounting device
- 1.1: perspective
- 1.2: Side
- 1.3 Opposite side
- 1.4: Top
- 1.5: Bottom
- 1.6: End
- 1.7 Opposite end

The design concerns a device (arm) that is mounted to a table for an MR scanner and is intended to be used for supporting/hanging devices like nurse call buttons or headphones.
